UNITED STATES PATENT OFFICE.

CLYDE E. W. GARDNER, OF DETROIT, MICHIGAN, ASSIGNOR, BY MESNE ASSIGNMENTS,
TO BURROUGHS ADDING MACHINE COMPANY, OF DETROIT, MICHIGAN, A CORPOR-
ATION OF MICHIGAN.

CARRIAGE FOR RECORDING MECHANISM.

1,151,454.

Specification of Letters Patent. Patented Aug. 24, 1915.

Application filed November 13, 1909. Serial No. 527,787.

To all whom it may concern:

Be it known that I, CLYDE E. W. GARDNER, a citizen of the United States, and resident of Detroit, in the county of Wayne and State of Michigan, have invented certain new and useful Improvements in Carriages for Recording Mechanism, of which the following is a specification.

My invention relates to the paper supporting and feeding devices for recording mechanisms where a rotatable platen is employed, and consists in means for holding the paper upon the platen without obscuring the same, means for supporting the paper in proper position to feed to the platen, and in details of construction hereinafter set forth and illustrated in the accompanying drawing, in which:

Figure 1 is a plan view of a sliding carriage and platen adapted for use with adding machines and embodying my improvement; Fig. 2 is an end view of the carriage, platen and adjuncts; and Fig. 3 is a cross section of the carriage and platen.

The platen A is a cylindrical platen which, as shown, is supported in a carriage B adapted to slide on the frame C of the machine, but some of the features of my improvement are not limited to use with the particular type of carriage and support shown.

Means are used for rotating the platen step-by-step, to which end a ratchet wheel 2 is connected to the platen or its shaft at one end and a pawl 3 engages the said ratchet wheel to rotate the same and the platen. In order that the pawl may not interfere with the rotation of the platen in either direction, except when the platen is being rotated by the pawl, I so support the latter that it is only in engagement with the ratchet wheel during the act of rotating the same. Thus the pawl 3 is pivoted to a swinging carrier or arm 4 and is carried by a spring 5 to a position to insure the engagement of the end of the pawl with the ratchet wheel as the carrier 4 swings in the direction of its arrow Fig. 3, but a bearing upon the carrier is arranged to contact with a bearing pin 38 upon the pawl so as to swing the latter away from the ratchet wheel after the wheel has been turned to a suitable extent. The platen can then be

turned in either direction by means of a knob at the end of its shaft.

With the platen is combined a series of carriers D, each of which supports a plurality of presser rolls 8, 9, two rolls being shown on each carrier and the parts being so constructed that all of the front rolls 8 will be supported in the position forward and near the top of the platen, whereby the sheets which are being printed will be supported until their lower edges are almost in printing position at the top of the platen. The carriers as shown consist each of two parallel side pieces 10, 10, curved to correspond to the curvature of the platen and set with their edges toward the platen so as to not only secure strength and rigidity but also so as to guide the paper with the least possible friction and to obscure as small a portion of the platen or paper as possible, and these side pieces are connected by cross-bars 12 upon which turn the presser rolls 8 and 9, the cross-bars and side pieces constituting in fact the carrier frame.

Each carrier is centrally supported, that is at some point between its opposite ends, by means of a suitable support E which as shown is in the form of a frame or bracket having flat side pieces, 13, 13 and cross-bars 14, 15, the latter constituting also the pivot or rock-shaft supporting the bracket to which the carrier is pivoted at x, and a spring 16 is connected to the cross-bar 14 and at the opposite end to a stud upon the carriage so as to swing the bracket and carry the forward end of the latter and the carrier D toward the platen.

It will thus be seen that there is combined with the platen a series of parallel separated presser rolls arranged at opposite sides of the platen, and as a result of this arrangement absolute control of the paper is secured. This ensues from the fact that the presser rolls are independent of each other and upon opposite sides of the platen, may swing to and from the latter, and will grip the paper firmly even should one of the rolls become smaller through wear and shrinkage, or if there should be any yielding of any part of the structure. In other words, each pair of rolls is held firmly up to the platen by its individual spring and will grip the paper firmly, and if the paper

is double or if the number of sheets presented at different parts of the platen is not the same there is a secure grip upon each, while all the carriers may yield individually and adapt themselves automatically to the paper without binding or retarding the same. It will also be seen that inasmuch as each carrier is centrally pivoted, or pivoted between its ends, the roll at either end 10 may readily swing away from the platen to permit the insertion of the paper between the two without disturbing the position of the roll at the opposite end. Inasmuch as there are no thin sheet metal parts, as is common in structures of this character, there is no liability of the carriage to get out of order by the accidental bending and jamming of such parts, while the construction is one which will insure cheapness of manufacture.

While the brackets which support the carriers may be differently constructed I have shown them as so arranged that the upper edges or faces of the side pieces 13, 13 are straight and on a plane about tangential to the lower face of the latter at the point where the lower presser roll bears upon the same, as shown in Fig. 3, and extending backward and upward at such an angle that 25 when the sheet is placed upon these edges they will support and guide the paper, without manipulation, directly to the gripping point between the platen and presser roll so that it will be caught by simply turning the platen by means of its knob. In order to secure a more extended support however I make use of the frame F which supports the shaft or spindle 20 of the paper roll X, and so construct the latter that the upper edges 30 of the side pieces of the said frame are upon the same plane as the upper edges of the brackets E.

In order to easily release the paper from the grip of the pressure rolls I preferably 45 make use of a cam shaft 43 which may be made rectangular in cross section and which extends longitudinally of carriage B immediately below the guide arms 44 of the support E. This shaft is pivoted at its ends in 50 the carriage B and is adapted to be turned by the arm and finger piece 45 secured thereto in convenient position at the end of the carriage. It will be observed that because of its irregular cross section this shaft 55 in turning will elevate arms 44 and thus release the rolls 8 and 9 from the platen and the paper thereon.

Where the carriage is a sliding carriage it is common to make use of some kind of 60 stop devices for arresting the carriage in

different positions especially when it is desired to print items in column. As illustrated in the drawings I prefer for this purpose to make use of a screw-threaded shaft 30 carried at its ends by arms 31 pivoted 65 at 33 to a portion of frame C, and in such position that the shaft 30 will normally be parallel with and immediately adjacent the edge 34 of frame C. Springs 35 secured to the arms and the frame tend to keep the 70 shaft against the edge 34. Adjustable lengthwise of this shaft are flat-sided nuts H which have transverse grooves, and the flat sides of these nuts are normally pressed against the edge 34 by the action of spring 75 35, and thus they are prevented from accidentally turning and are maintained in adjusted positions. A finger 32 on shaft 36 mounted on carriage B enters the transverse groove in the nuts and maintains the carriage in position. An operating arm or finger piece 37 is secured to shaft 36 for the purpose of rocking it to release finger 32 from the groove in the nut.

No claim is herein made to the particular 85 form of stop device hereinbefore described, as the same is claimed in a divisional application filed May 25, 1915, Serial Number 30,337, or the line spacing mechanism.

Without limiting myself to the construction shown, I claim:

1. The combination with a cylindrical platen of a plurality of swinging supports each having side arms extending substantially tangent to the platen and all of said 95 arms constituting paper guides, a plurality of curved carriers each pivotally connected between its ends to one of the swinging supports, and parallel presser rolls on each carrier.

2. The combination with a rotatable platen, of a carrier, two presser rolls on said carrier adapted to respectively bear on the platen in front and above the axis and below and in rear of such axis, a swinging support for said carrier having a section extending rearwardly and upwardly from the lower presser roll and substantially tangential to the platen, and a rotary cam shaft 105 extending beneath the rearwardly inclined section of said support and adapted to rock said support to move the presser rolls from the platen.

In testimony whereof I affix my signature in presence of two witnesses.

CLYDE E. W. GARDNER.
